WASTE HEAT BOILER

Charles V. McIntire, Short Hills, N. J., and Lloyd F. Schrader, Bellrose, N. Y., assignors to Semet-Solvay Engineering Corporation, New York, N. Y., a corporation of New York

Application April 14, 1934, Serial No. 720,538

5 Claims. (Cl. 122—7)

This invention is directed to waste heat recovery apparatus, and more particularly, to a waste heat boiler for use in connection with a water gas set and adapted to be heated by blast 5 gases from the set during the blasting cycle and by heat generated in an auxiliary fluid fuel fired unit during the water gas making cycle.

Heretofore, it has been proposed to employ a waste heat boiler to receive blast gases from a water gas set during the blasting cycle and during the water gas making cycle to be heated by 10 products of combustion generated in a combustion chamber such as a Dutch oven. To prevent overheating of the brick work of the combustion 15 chamber or Dutch oven, air was circulated through a jacket surrounding the brick work. In order to maintain a reasonably low flame temperature in the combustion chamber, a large excess of air was introduced to support the combustion of the oil or other liquid fuel burned. Without such excess of air, fluxing of the 20 refractory lining would take place. While the air passed into the combustion chamber serves as a carrying medium for delivering heat to the boiler, an excess of air necessarily results in an increased volume of stack gases with resultant 25 increased heat losses.

An object of the present invention is to provide a combined waste heat boiler and combustion 30 chamber which is more economical to construct and which is more efficient in operation. Other objects and advantages of this invention will appear from the following detailed description.

In accordance with this invention, a waste 35 heat boiler, such for example as the vertical type waste heat boiler provided with an upright boiler drum communicating with a steam and water drum, is equipped with a water jacketed combustion chamber. Products of combustion generated in the combustion chamber may be passed 40 through the boiler drum during the water gas making cycle to supply the heat necessary to generate steam. The water jacketed portion of the combustion chamber is communicably connected with the steam and water drum and also 45 the boiler drum so that the circulation of water takes place from the boiler drum through the water jacket into and through the steam and water drum, back to the boiler drum. Due to this circulation, the combustion chamber jacket becomes 50 part of the boiler and the inner shell of the combustion chamber serves as an active steam generating surface.

A considerable amount of heat is absorbed in 55 the water jacket by direct radiation from the

flame resulting from the combustion of oil or other fluid fuel. This serves the useful purpose of generating steam in the jacket and at the same time results in a tempering of the gaseous products of combustion which are passed 5 to the boiler from the combustion chamber. Cooling of the gaseous products of combustion thus effected minimizes, if it does not eliminate, loosening of the tubes in the upper tube sheet 10 of the boiler due to overheating of the tube sheet, and deterioration of the brick lining in the duct or passageway connecting the water jacketed combustion chamber with the waste heat boiler caused by overheating of the brick-work with consequent surface fusion and slagging. 15

Among the important advantages of the combined water jacketed combustion chamber and waste heat boiler, as compared with the air-cooled Dutch ovens heretofore employed, the 20 following may be mentioned.

(1) Higher thermal efficiencies due to direct exposure of the heated surfaces of the water jacket to high temperature radiation from the flames produced in the combustion chamber and 25 also due to a reduction in stack losses;

(2) Lower operating costs due to elimination of brick lining upkeep expense and increased life of the tube sheets; and

(3) The equipment is more simple in design 30 and can be constructed at lower costs.

In the preferred embodiment illustrated on the drawing, the invention is shown incorporated in a water gas set equipped with a combined waste heat boiler and water jacketed combustion chamber and the present disclosure will be confined to the present illustrated embodiment of the invention. It will be understood, however, that the novel features and improvements are susceptible to other applications, such for example as other 40 types of boilers than the vertical type shown in the drawing. Hence, the scope of this invention is not confined to the embodiment herein described.

In the accompanying drawing, forming a part 45 of this specification and showing for purposes of exemplification a preferred form of this invention without limiting the claimed invention to such illustrative instance, the single figure is a side elevation, partly broken away, of a water gas 50 set equipped with the waste heat boiler and combined water jacket embodying this invention.

In the drawing, reference numeral 10 indicates a water gas generator having a bed of fuel 11 which may be of coal or coke. The generator 55

10 communicates with the carburetor 12 by means of connection 13 disposed to connect the top of the generator with the top of the carburetor. Carburetor 12 may be provided with checker-brick 14 as is customary and communicates by means of passage 15 with the superheater 16 provided with checkerbrick 17. The top of the superheater is provided with a blast cap 18 arranged to be operated by hydraulic cylinders 19. 5
 10 of any well known type. As customary, a stack 20 is disposed above the superheater. A line 21 leads from the superheater into housing 22. Backrun line 23 leads from the bottom of the generator beneath the grate to the housing 22. 15
 15 A three-way valve 24 is disposed in the housing 22 and is arranged to interrupt the flow from the line 21 into the housing 22 and simultaneously permit flow from backrun line 23 into the housing and vice versa. Operation of the three-way valve 24 may be accomplished by a rack and ratchet mechanism indicated generally by the reference numeral 25, the rack being actuated by a hydraulic cylinder or motor 26. Housing 22 communicates by means of pipe 27 with wash-box 28 provided with an offtake 48 leading to a holder or other suitable point. 20
 25

Air for blasting and secondary air for supporting combustion of the blast gases may be admitted to the generator through lines 31 and 32, respectively. These two lines are supplied from the main line 33 and flow of the blasting air and secondary air controlled by valves 34, 35 which are arranged to be operated by hydraulic cylinders 36, 37. A valve 41 operated by hydraulic cylinder 42 controls the flow of uprun steam through pipe line 79 leading into the base of the generator. A like valve 43 controlled by hydraulic cylinder 44 controls the flow of back-run steam into the superheater. Flow of oil into the carburetor may be controlled by hydraulically operated valve 45. 30
 35
 40

The top of the superheater is connected by a passage 49 with the top of the waste heat boiler 50. A valve 51 in passage 49 controls flow there-through and operation of valve 51 may be effected by hydraulic cylinder 52. The waste heat boiler may be of any well known type but preferably is of the fire tube type and as indicated on the drawing may comprise tube sheets 53, 54 in which the tubes 55 are disposed in the manner well known in the boiler art. The tube and tube sheets are mounted in the boiler drum 56 inclined somewhat to the vertical as shown in the drawing. A steam and water drum 57 is disposed to one side and somewhat above the top of the boiler drum 56. This drum 57 may be supported on a bracket extending from the top of the boiler drum. The base portion of the steam and water drum has leading therefrom one or more down-comer tubes 58 which connect the bottom of the steam and water drum with the base portion of the boiler drum 56. One or more upcomer tubes 59 may be employed to connect the steam and water drum with the top portion of the boiler drum 56. Circulation of water takes place from the top of boiler drum 56 through tubes 59 into the steam and water drum 57, then through tubes 58 into the base portion of the boiler drum 56. The base portion of the vertical drum 56 beneath the tube sheet 54 is formed with a gas outlet 61 which communicates with a stack 62. 45
 50
 55
 60
 65
 70

In accordance with this invention, a water jacketed combustion chamber 63 is placed in communication with the gas flue 64 leading into the gas inlet of the waste heat boiler 50. The

combustion chamber is preferably disposed somewhat below the steam and water drum 57. It may be composed of an inner metal corrugated shell 65 and an outer metal shell 66 forming a space for the reception of liquid preferably water. 5
 10 A refractory lined flue 67 connects the combustion chamber with the gas inlet 64 of the waste heat boiler. A fluid fuel burner such as an oil or gas burner 68 extends into the combustion chamber. Flow of fluid fuel such as oil to this burner is controlled by a valve 69 of any well known type, operation of which may be effected by hydraulic cylinder 71. Air is supplied to the burner by a blower 77 communicating with a line 78 extending into the combustion chamber 63. A valve 46 15 in line 78 controls the flow of air under pressure to the burner. Operation of valve 46 may be effected by a hydraulic cylinder 47. 20
 25

Leading from the base of the boiler drum 56 is a pipe 70 provided with branched extensions 20 71 extending into the water jacket. The upper portion of the water jacket is preferably provided with a plurality of conduits 72 connecting the water jacket with the steam and water drum 57. 25

Each of the hydraulic cylinders controlling the valves for admitting air and steam to the fuel bed, oil to the carburetor, flow of blast gases through the waste heat boiler, flow of gas through the set and the flow of air and oil to the water jacketed combustion chamber is supplied with pressure fluid from a common source. The flow of pressure fluid to these hydraulic cylinders and the discharge of the pressure fluid therefrom is controlled from a central control nest 73 which 30 may be of any well known type. As shown on the drawing, the control nest may involve a shaft 74 rotating at substantially constant speed and provided with a series of cams, one for each hydraulic cylinder, and arranged to operate valve mechanism controlling the flow of pressure fluid to and the discharge of pressure fluid from each hydraulic cylinder. Such valve mechanisms may be of any type well known in the gas art and are indicated diagrammatically on the drawing by 35 the reference numeral 75. The lines connecting each hydraulic cylinder with the valves are indicated by the reference numeral 76. As the control mechanism per se and the connections thereof to the hydraulic cylinder may be of any 40 well known type, this mechanism has been depicted on the drawing somewhat schematically. 45
 50

In operation, the fuel bed 11 may be blasted with air and the resultant blast gases burned in the carburetor and superheater to heat the 55 checkerbrick therein, combustion of the blast gases being supported by secondary air admitted through pipe 32. The products of combustion pass through flue or line 49 into the waste heat boiler 50, through the tubes heating the water surrounding the tubes and then through outlet 61 to the stack 62. Upon the completion of the blasting cycle, which may be of approximately two minutes duration, the introduction of air to the set is interrupted. This is accomplished by operation 60 of the control nest which functions to effect closing of the valves controlling the flow of air into the set and also valve 51 which controls flow through flue 49 into the waste heat boiler. These valves, it will be understood, were opened to effect 65 blasting of the fuel bed to permit the flow of blast gases through the waste heat boiler. Concurrently with the closing of the aforementioned valves, the control nest effects the opening of the steam valve 41 for admitting uprun steam to 70 75

the generator. The steam reacts with the fuel bed to form water gas which passes through the carburetor where oil is admitted, carburetted water gas passing through the superheater into the washbox 28, the three-way valve 24 having been operated to close the line 23 and open the line 21.

Simultaneously with the introduction of steam to the fuel bed, the control nest effects the opening of valves 46 and 69 to admit air and oil or other fluid fuel to the water jacketed combustion chamber 63. The products of combustion generated pass through flue 67, through the tubes in the waste heat boiler, heating the water surrounding the same and leaves outlet 61 entering stack 62. A considerable amount of heat is absorbed in the water jacket by direct radiation from the flame produced therein. This serves the useful purpose of generating steam in the jacket. As hereinabove indicated the gases formed in the combustion chamber are tempered by the water circulated through the water jacket. Steam produced in the water jacket passes through tubes 72 in the form of steam bubbles entrained in water, and these bubbles lift a relatively large quantity of water through the tubes and discharge it into the steam and water drum 57. Water enters the water jacket through pipe 70, to replace that portion converted into steam and carried by the steam into the steam and water drum 57. The circulation of water thus established causes the combustion chamber jacket to become part of the boiler, the inner shell of the chamber functioning as an active steam generating surface.

At the completion of the uprun cycle, which may be of about two minutes duration, valve 41 and three-way valve 24 are operated, valve 41 being closed and three-way valve 24 being moved into position to close line 21 and open line 23. The backrun steam inlet is simultaneously opened, backrun steam passing through the superheater, carburetor, down through the fuel bed in the generator, the resultant water gases passing through the backrun line into the washbox. Concurrently with this operation, oil or other fluid fuel and air are admitted to the combustion chamber and products of combustion pass through the waste heat boiler as hereinabove described. Upon the completion of the backrun cycle, which may be of about one minute duration, the admission of oil and air to the combustion chamber is interrupted, backrun steam inlet closed, three-way valve 24 operated to close line 21, and the blasting cycle commenced as hereinabove described.

Since different embodiments of the invention could be made without departing from the scope of this invention, it is intended that all matter contained in the above description or shown in the accompanying drawing shall be interpreted as illustrative and not in a limiting sense.

We claim:

1. In a waste heat boiler, a main upright boiler drum having gas passageways therethrough, a steam and water drum, upcomer means connected to deliver from the upper portion of the main drum to the steam and water drum, downcomer means connected to lead water from the steam

and water drum to the lower portion of the main drum, a water jacketed fluid fuel fired combustion chamber communicably connected with the upper portion of the main drum, means connecting the water jacket with the lower portion of the main drum and with the steam and water drum for circulation of water from the main drum through the water jacket into and through the steam and water drum, and means for burning fluid fuel in the combustion chamber and conducting the products of combustion therefrom through the main drum. 5

2. A waste heat boiler comprising, in combination, a drum adapted to contain liquid, means for generating and passing hot gases through said drum from one end to the other thereof to heat said liquid by heat exchange therewith, a liquid jacketed combustion chamber, other means for generating products of combustion in said combustion chamber and passing the same through 10 said drum along the path traversed by said hot gases and tubes connecting said jacket with said drum for passing liquid from said jacketed combustion chamber to said drum. 15

3. A waste heat boiler comprising, in combination, a drum having fire tubes therein extending from one end to the other end thereof and adapted to contain liquid surrounding said tubes, means for passing waste gases through said tubes to heat said liquid by heat exchange therewith, 20 a combustion chamber, a liquid jacket substantially surrounding said combustion chamber, and means for generating products of combustion in said combustion chamber and passing the same through said tubes, said liquid jacket being connected to said drum by means including tubes whereby liquid is circulated through said jacket and said drum. 25

4. A waste heat boiler comprising, in combination, a boiler drum having tubes therein and adapted to contain liquid surrounding said tubes, a steam drum communicably connected to said boiler drum by tubes, means for passing waste gases through said first mentioned tubes to heat said liquid by heat exchange therewith, a liquid 40 jacketed combustion chamber communicably connected to said boiler drum by upcomer and downcomer tubes, whereby liquid recirculates between said drums and chamber, and means for generating combustion gases within said chamber 45 and passing them through the tubes in said boiler drum. 50

5. A waste heat boiler comprising, in combination, a boiler drum, a vapor drum, tubes communicably connecting said vapor drum with the boiler drum for circulation of liquid therebetween, a liquid jacketed combustion chamber located exteriorly of said boiler drum, tubes connecting said liquid jacket with said boiler drum and said vapor drum for circulation of liquid therebetween, 55 means for communicably connecting said combustion chamber with said boiler drum for passage of products of combustion from said chamber through said boiler drum, and means for burning liquid fuel in said combustion chamber. 60
